Primary Examiner — David Muller(74) *Attorney, Agent, or Firm* — The Webb Law Firm(57) **CLAIM**

The ornamental design for a T-shaped cap for a medical injector, as shown and described.

DESCRIPTION

FIG. 1 is a perspective view of a T-shaped cap for a medical injector in accordance with the present invention

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, shown engaged with an injector.

The broken lines representing the interior portion of the cap shown in FIGS. 6 and 7 and the injector shown in FIG. 8 represent disclaimed subject matter and form no part of the claimed design.

1 Claim, 8 Drawing Sheets(56)
